Application August 31, 1955, Serial No. 531,788

9 Claims. (Cl. 271—62)

The present application relates to sheet feeding apparatus and more particularly to improved apparatus for feeding a supply of sheets or boards to a transfer station from which the sheets are to be removed for further processing.

Various devices have been proposed in the past for the supply and feeding of a plurality of sheets to a transfer station from which the individual sheets are to be removed for a desired operation. Some of these prior devices present problems and disadvantages in operation. Such problems may involve the matter of replenishment of the supply of sheets or boards and the problems of limitation of the apparatus to a single size of sheet or board.

With these and other problems of the prior art in view, one object of the present invention is to provide an improved apparatus for feeding a supply of sheets to a predetermined transfer station.

A further object is a sheet feeding apparatus in which the individual sheets are fed by contact of an edge of each sheet with a moving belt.

A further object is the provision of improved follower mechanism for movement of such sheets with a feeding belt.

Still another object is an improved follower arrangement providing simple and efficient replenishment of the sheet supply without interruption of the feeding operation.

Another object is the provision of an improved driving mechanism and improved controls for such a sheet feeding apparatus.

A further object is the provision of improved driving mechanism operable in combination with an associated conveyor member which is designed to handle the sheets as they leave the sheet supply transfer station.

Still another object is a sheet feeding apparatus in which provision is made for convenient adjustability to accommodate a plurality of different sheet sizes.

Other objects and advantages will be apparent from the following specification in which certain preferred embodiments of the invention are described with particular reference to the accompanying drawings. In these drawings, in which like reference characters indicate like parts,

Figure 1 is a side view of the device according to the present invention, with certain portions broken away and certain portions shown in section for clearness;

Fig. 2 is a top view of the device of Figure 1 with the supply of sheets and certain other elements removed and with some of the parts placed in different adjusted positions for convenience of description and illustration;

Fig. 3 is a partial side view showing details of the adjustable mounting for the upper guide member;

Fig. 4 is a sectional view on the lines 4—4 of Fig. 2;

Fig. 5 is a sectional view on the lines 5—5 of Fig. 2; and

Fig. 6 is a partial view taken from the line 6—6 of Fig. 2 showing details of the driving mechanism of the feed-
ing device.

General description

As illustrated in Figs. 1 and 2, the device of the present invention is designed to move a supply of sheets or boards indicated generally at 10 to a predetermined transfer station at which the boards are to be operated on by another member. In this case, the individual boards or sheets in the supply 10 are moved toward the transfer station by engagement of one edge of each board with a moving belt 12. In the embodiment shown in the drawings, the belt 12 includes a horizontal portion on which the bottom edges of the sheet members rest. In appropriate cases, the orientation of the belt portions 12 can be modified to meet particular operating conditions.

A guide member 14 is spaced from the belt as described below to position the sheets at the desired angle as they approach the transfer station. One or more inclined ramps, such as that shown at 16, engage the leading sheet to hold it at the transfer station.

The transfer station is indicated in Fig. 1 by the position of the leading sheet 18. From this transfer station, the leading sheet is to be removed by suitable apparatus which forms no part of the present invention. One form of apparatus for this purpose is described in detail below.

The invention provides special follower means for maintaining the sheets in position on belt 12 and for assisting belt 12 in urging the sheets toward the transfer station. The follower means includes one or more follower members and preferably a combination of two such members, particularly designed to provide a simple and convenient method of replenishing the supply when necessary. Special driving and control means are provided to move the belts and a follower member toward the transfer station, so that a new sheet will be presented at the transfer station whenever the previous sheet is removed from that point. Details of the various parts, including the driving mechanism, the reloading mechanism and the control features are set forth in greater detail below, together with a description of the means by which the apparatus can be adjusted to accommodate a plurality of different sizes of sheets.

Transfer mechanism.

As an illustration of one type of transfer or operating apparatus with which the present sheet supply mechanism is particularly useful, Figure 1 discloses a transfer mechanism by which sheets are removed one at a time from the transfer station and deposited on the upper surface of a horizontal conveyor member. For this purpose, the transfer mechanism illustrated includes suction members 20 and 22 adapted to engage the leading sheet and to grip said sheet by application of a suitable vacuum within the cups. The suction cups are carried by a transfer member 24 supported by two pivoted links 26 and 28. Certain features of this particular transfer mechanism are described and claimed in a co-pending application of Robert H. Duncanson, Serial No. 531,804 filed of even date herewith. As described in more detail in that application, the links 26 and 28 are located and operated in such a manner as to move the leading sheet 18 from its initial transfer station to a horizontal position on the top of the conveyor belt portion 30.

The conveyor belt portion 30 is supported by a suitable conveyor wheel 31 driven with a rotary shaft 32. In the present case the shaft 32 rotates intermittently. It moves the belt 30 a sufficient distance at each intermittent rotation to advance one sheet or board away from the transfer mechanism and thus provide space for deposit of the next sheet. The link 26 of the transfer mechanism is reciprocated by a connecting rod 34 driven in the manner described in the above co-pending application in timed

sequence with the movement of conveyor shaft 32 and conveyor belt 30.

Other appropriate transfer devices or other operating mechanisms could be used in lieu of this specific transfer mechanism in appropriate cases for desired operations on sheets presented successively at the transfer station 18. The mechanism of the co-pending application as illustrated in Figure 1 does provide a smooth and efficient combination, however, which, together with the present sheet supply apparatus, facilitates the movement of individual sheets to a processing station such as that represented by the horizontal portion of conveyor belt 30.

Sheet feeding mechanism

As set forth most clearly in Figs. 1 and 2, the individual sheets are fed toward the transfer station by engagement of their lower edges with one or more movable belts, such as the belt 12. In the present apparatus, three such belts are provided as shown in Fig. 2. The belts are designated as 12, 36 and 38, respectively. Belt 12 is supported and driven by a suitable pulley or sheave 40, while belts 36 and 38 are similarly carried and driven by sheaves 42 and 44, respectively. All of these pulleys or sheaves are suitably keyed to and driven by a rotary shaft 46, which is rotated by mechanism described below to advance the belts and move sheets to the transfer station as needed.

The rearwardly disposed ends of each of the belt portions 12, 36 and 38 are supported by similar pulleys 48, 50 and 52 carried on a shaft 54 supported for free rotation in bearings 56 and 58. Suitable guides are provided for the edges of the sheets to maintain them in the desired lateral alignment as they are fed toward the transfer station. For example, one edge of the apparatus is provided with stationary guide members 60 and 62 carried on vertical supporting brackets 64 attached to the main frame. An adjustable guide 66 is provided for the opposite edge of the sheets and the method of support and adjustment for this guide member 66 is described in detail below.

Follower mechanism

According to an important feature of the present invention, an improved follower mechanism is provided to assist the belts in moving the sheets to the transfer station. The follower mechanism is particularly designed and adapted to maintain the sheets at the desired angle for presentation to the transfer station. The follower arrangement is also adapted to simplify the reloading operation as additional sheets are needed.

To accomplish these objectives the invention contemplates the combination use of two improved follower units. One of these units is indicated at 68 in the form of a cross bar adapted for engagement with the two outside belts 12 and 36. The cross bar or body portion 68 of the follower carries an upwardly extending pusher member 70 and a horizontal base portion 71 attached at 72 to the body member 68. The pusher portion 70 is disposed at a predetermined angle designed to hold the rearwardly located sheets or boards at exactly the angle desired for the leading sheet at the transfer station.

To hold the follower member 68 in position during its movement toward or away from the transfer station a suitable track 74 is attached by bolts 76 to the base plate 78 of this portion of the machine. With particular reference to Figs. 2 and 4, the follower 68 includes a longitudinally extending guide or slide portion 80 adapted to engage the track 74 and insure movement of the follower 68 in a direction parallel to the belts. At the same time, this arrangement of the parts insures maintenance of the follower 68 in its position extending perpendicularly across the direction of feeding movement of the belts. This guide portion 80 includes flanges 82 adapted to engage beneath the edges of the track member 74. The guide member is attached to the cross mem-

ber 68 by bolts 84 and is received in an appropriate cross-notch or channel in member 68 to maintain the parts in the desired relative orientation. Guide 80 and track 74 hold the follower portion 70 at the desired upright angular position, where the belts alone might not have sufficient rigidity to prevent tipping of the portion 70 out of such position.

In order to drive the follower member 68 with the belts, improved mechanism is provided to clamp the follower member in driving engagement with the belts and to release such clamping engagement during re-loading of the apparatus.

For this purpose, the follower member 68 includes a fixed clamping member 86 attached by bolt 88 at one edge of the follower. This fixed clamp 86 is located immediately adjacent the outer edge of belt 12 and includes an angular face adapted to fit one angular lateral face of belt 12 as illustrated in Fig. 4. A cooperating movable clamp member 90 is provided to engage the other lateral face of belt 12. Member 90 is carried by a vertical pin 92 and supported for lateral movement in a slot 94 in the member 68. One end of a lever arm 96 engages the pin 92 to provide the desired clamping and unclamping movement of member 90.

In similar manner, another fixed clamping member 98 is mounted on the outer edge of the other outside belt 36 and is fixed to the follower member 68 by a bolt 100. A cooperating movable clamp member 102 is supported on a vertical pin 104 movable cross-wise of the belts in a slot 106. One end of a lever 108 carries the pin 104 and provides the desired clamping and unclamping movement of member 102. As indicated particularly in Fig. 4, the angular disposition of the lateral edges of the respective belts and associated clamping members not only provides for driving engagement between the belts and the follower members 68, but also assists in preventing any upward removal or undesired rocking action of the follower member 68 with respect to the belts 12 and 36.

The operating mechanism for the clamps is best seen in Fig. 2. As shown in this view, the remaining ends of lever arms 96 and 108 are pivoted to each other by a vertical pin 110. The location of this pivot point or pin rearwardly of the transverse line defined by the pins 92 and 104 of the clamping members provides in effect a toggle linkage. This toggle tightens the clamping engagement of the parts with the belts when pivot point 110 is moved toward the transfer station and disengages the clamping members when the pivot pin 110 is moved rearwardly.

For convenience in operation of this toggle linkage, an actuating arm 112 is provided. One end 114 of this arm is pivoted at 116 to an outer edge of the follower member 68. The other end of the actuating arm 112 carries a suitable finger piece 118. A spring 120 is connected at one end to the actuating arm 112 and at the other end to a suitable connection 122 on the follower member 68. Pin 110 of the toggle linkage engages a suitable hole or slot (not shown) in the lever arm 112. Under the action of spring 120 the lever arm is urged toward the transfer station and thus the spring tends to maintain the clamping engagement of the parts for movement of the follower member 68 with the belts 12 and 36.

When it is desired to withdraw the follower member, for example in order to replenish the supply of sheets carried by the belts, it is merely necessary to pull rearwardly on the handle piece 118 against the resilience of spring 120. This action will move the pivot pin 110 rearwardly and disengage the clamps from the belts, so that the follower members 68 can slide rearwardly along the path determined by engagement of guide 80 with track 74. The relative location and orientation of the parts provides for convenient operation during reloading. Thus the application of force to lever 112 in a rearward direction not only disengages the clamps, but also moves the follower rearwardly as desired.

Auxiliary follower mechanism

The other of these units, according to a special feature of the present invention, is an auxiliary follower member designated generally at 124 (Figure 1) is provided. One of the primary purposes of this follower member is to maintain the existing supply of sheets at the desired angle for presentation to the transfer station. Thus the auxiliary follower assists in supporting the upper edges of the sheets and prevents the transmission of undesired excessive forces to the lower follower member 68 and its pusher portion 70. This follower also urges the sheets toward the transfer station when the follower 68, described above, is retracted for insertion of an additional supply of sheets.

Follower 124 includes a body portion 126 adapted to engage and be supported by the upper edges of one or more of the rearwardly located sheets in the supply. The follower also includes a depending flange 128 adapted to engage behind the rearmost sheet of the supply. An upward extension of the flange 128 provides a suitable finger piece 130 for manipulation of the follower 124. A screw or other connecting member 132 on the follower 124 provides means for attachment of one end of a flexible tensioning member 134.

The follower also includes a switch actuating portion 136, in the form of an inclined cam adapted to engage and lift the operating arm 138 of a suitable switch 140. Switch 140 is connected by wires 139 and 141 to the power means (not shown) controlling the vacuum pump which applies suction to the transfer mechanism. The switch 140 may also be connected in circuit with switch 248 (described below) to stop further feeding movement of the card supplying belts 12, 36 and 38, whenever the supply of boards or sheets is depleted to the point where the follower portion 136 engages the switch arm 138.

As indicated below, suitable signal devices are provided to warn the operator when the supply is nearing this stage of depletion. In case the signal is ignored, switch 140 will stop the operation of the suction pump and card advancing mechanism.

In order to urge the follower 124 toward the transfer station, the flexible tensioning member 134 has its remote end attached to a suitable weight member 142. Between the follower 124 and weight member 142 a suitable system of pulleys is provided to guide the flexible tensioning member 134 through a desired path. Thus, the end of the tensioning member 134 nearest the follower 124 first passes around the pulley 144 (Fig. 2) supported on the adjustable upper guide support 146 by a vertical shaft or pivot 148. The pivot is in the form of a screw member which is laterally adjustable along the support 146 by means of a lateral slot 150.

The pivot screw also holds the upper guide 14 on support 146. For this purpose, the guide has portions 152 which fit the support for sliding movement along the support when the screw 148 is loosened. Switch 140 is also supported on guide 14 by an arm 154. Thus the lateral position of the follower member 124, upper guide 14 and switch 140 can be shifted with respect to support 146 to accommodate different widths of sheets.

From the pulley 144 the line 134 passes laterally to a pair of pulleys 156 and 158. As viewed in Fig. 2, the line 134 passes beneath pulley 156 which is rotatable on a horizontal axis parallel to the direction of movement of the feed belts. After passing beneath pulley 156 the line extends upwardly over and around pulley 158 which is rotatable on a horizontal axis oriented laterally across the direction of movement of the feed belts. Pulley 158 is in alignment with the rotatable drum 160, the effective pitch of which is the same as the effective pitch of the belts on the driving pulleys 40, 42 and 44. The line 134 passes around the periphery of this drum 160 one or more times to insure tight frictional driving engagement between the drum 160 and the line. The line then passes

over a suitable additional pulley 161 (Figure 1) and thus to the weight member 142.

The double pulley arrangement shown at 156 and 158 in Fig. 2 is designed to insure alignment of the line 134 with the drum 160 for all positions of vertical adjustment of the upper guide support 146.

The laterally projecting upper guide support 146 in turn includes a slide or guide portion 162 mounted for upward and downward adjustment along the inclined vertical support member 164. Member 164 in effect provides a trackway for the portion 162 and this upwardly extending trackway is connected to the frame of the apparatus at its base 166 by suitable bolts 168. Clamping bolts 170 and 172 threaded into the upper guide support portion 162 provide for clamping engagement of the edge portions 174 and 176 with the cut-away track portions 178 and 180 (Fig. 3). The support 164 extends at the same desired angle as the angle at which the sheets are to be held in the transfer station.

By means of this arrangement the vertical location of the upper guide supports can be varied to change its spacing above the belts 12, 36 and 38 in order to accommodate sheets of different vertical height. The angle of support 164 keeps the guide in the proper relative longitudinal location with respect to the transfer station in all positions of adjustment. No matter what position of adjustment is chosen for this purpose, however, double pulley arrangement 156 and 158 provides a convenient means of feeding the flexible tensioning member 134 directly to the periphery of drum 160, even through the angle at which the line 134 approaches drum 160 varies according to the adjusted height at which the guide support is located. If a single pulley were used in place of the double pulleys 156 and 158, this change in angle of approach could result in disengagement of the line from the single pulley in certain positions of adjustment.

Follower drum driving mechanism

The drum 160 which controls movement of the line 134 and thus controls movement of the upper follower 124 under the influence of its weight member 142, includes a lateral driving face 184 (Fig. 5). Friction clutch members 186 are adapted to engage this face 184 to rotate the member 160. The drum 160 is supported by a hub or bearing portion 182 for free rotation on the shaft 46 which drives the belt members.

The clutch surfaces 186 are carried by a clutch member 188 which is also mounted on shaft 46. A cross pin 190 passes laterally through the clutch member 188 and also through the slot 192 in shaft 46. The pin and slot arrangement provides for positive rotation of the clutch member 188 with shaft 46, but permits limited axial movement of clutch member 188 along the shaft.

One end of a spring member 194 engages the clutch member 188 on the side opposite the drum 160. The other end of the spring 194 engages the opposed surface of pulley member 40 which is fixed to the shaft 46. Spring 194 is under compression and thus normally urges the clutch member 188 toward the drum 160 so that the surfaces 186 are in frictional driving engagement with the surface 184 of the drum. With the parts in this position, the drum 160 will be rotated at the same angular speed as the pulleys 40, 42 and 44. Thus the cord or line 134, which is wound around the drum 160, will be permitted to move at the same linear speed as the belts 12, 36 and 38. This movement will urge the upper follower member 124 toward the transfer station whenever the belts are moved and in exact synchronism with the movement of the belts.

To provide for manual disengagement of the clutch, when it is desired to retract the upper follower member 124, suitable clutch operating mechanism is provided. In this case, a rod 196 is supported for axial movement within the center of shaft 46. One end 198 of rod 196 engages the cross pin 190. The other end of rod 196 car-

ries a manually operable knob or handle portion 200. Pressure against the end of this knob 200 in a direction extending axially along the shaft toward its opposite end, will force pin 190 and associated clutch member 188 to the left in Fig. 5 and out of engagement with drum 160.

Thus when the knob 200 is pushed inwardly, the drum 160 will be free to rotate. The follower member 124 can then be drawn rearwardly away from the transfer station against the urging of the weight member 142. Once the follower 124 has been engaged behind an additional supply of cards (which may be inserted as shown in Figure 1), the weight 142 will draw the follower into firm engagement with the cards so that all the cards are in abutting face-to-face engagement for subsequent feeding and supply movements. The clutch button 200 may then be released so that the clutch will again engage drum 160 and insure further movement of the line 134 and follower 124 in exact synchronism with the belt member.

Belt driving mechanism

As indicated above, another feature of the present invention is the provision of improved means adapted to drive the belt members to feed a new sheet to the transfer station whenever the previous sheet has been removed. In this case, the desired driving movement for shaft 46 is advantageously obtained from the conveyor shaft 32 of the main conveyor 30. Details of the driving mechanism are shown particularly in Figs. 1, 5 and 6. In the latter figures, a gear or ratchet member 202 is keyed at 204 to the belt drive shaft 46. Ratchet member 202 is provided with a series of ratchet teeth 205 around its circumference. Rotation of the ratchet gear will accordingly drive shaft 46 through identical angular movements.

For transmission of the desired actuating forces to the ratchet member 202, a clutch member 208 is also mounted on shaft 46. Clutch member 208 includes a hub portion 210 which is mounted for free rotation on shaft 46 as shown. The bearing portion 210 permits back and forth movement of the clutch member 208 in first one direction and then the other, i. e., in the desired angular direction of movement of shaft 46 and then in the opposite direction.

The desired reciprocating movement of clutch member 208 is obtained by means of a cam follower 214 attached to the lower end 212 of the clutch member by a suitable bolt or shaft 216. As shown particularly in Figure 1, the cam follower 214 is adapted to engage the surface of an appropriate cam 218 keyed at 224 to the main conveyor shaft 32. Cam 218 includes a plurality of raised portions 220 and intervening dwells or retracted portions 222. Spring 226, connected at 228 to the clutch member 208, pulls the cam follower 214 against the periphery of cam 218.

Rotation of shaft 32 thus causes the lower end 212 of the clutch member 208 to shift between the heavy and dotted line positions of Fig. 1 as the successive cam portions engage the follower 214. The number of cam projections and the extent of movement required by the cam for clutch member 208 are coordinated with the number and spacing of the ratchet teeth 205 to rotate shaft 46 far enough to replace the cards at the transfer station as needed.

To transmit the desired movements from the clutch member 208 to the ratchet member 202, a suitable pawl 230 is provided. The pawl is pivoted at 232 on clutch member 208. It includes a point or tooth 234 at one end, which is designed for engagement with the ratchet teeth 205. Thus movement of the clutch member 208 from right to left in Fig. 6 will rotate the ratchet member 202 whenever the pawl point 234 is in engagement with one of the teeth 205. The inclination of the teeth permits movement of the clutch member in the opposite direction without reverse rotation of ratchet member 202.

A spring 236 is connected to the pawl member 230 in such a manner as to urge the pawl point 234 normally

out of engagement with the ratchet teeth 205. The pawl member 230, however, includes an oppositely projecting lever arm portion 238 which is connected by a further spring 240 to the core member 244 of a suitable solenoid 246. When the solenoid is energized, the core member 244 is pulled downwardly in Fig. 6 and spring 240 is tensioned to rock the pawl 230 into engagement with ratchet teeth 205 against the urging of spring 236. When the solenoid 246 is de-energized, the spring 236 restores the pawl member 230 to its retracted or dis-engaged position.

Automatic control of belt feed

As indicated above, the desired feeding movement for shaft 46 is obtained in response to the absence of a sheet from the transfer station 18. For this purpose, a feeler or sensing arm 250 is located at one side of the supply of sheets so that the arm will be engaged and shifted by the leading sheet as the sheet actually enters the transfer station. Feeler arm 250 is carried by a suitable switch unit 248. The switch is connected in circuit with solenoid 246 and a suitable current source (not shown) by connecting wires 252, 254 and 256. When a sheet is in position at the transfer station, the switch is held in position to de-energize the solenoid. Thus the movement of clutch member 208 is not transmitted to shaft 46. But after one or more of the leading sheets is removed, the feeler arm moves and the solenoid is energized until the resulting movement of shaft 46 by the clutch members has brought another sheet into position. In one practical embodiment of the machine, the flexibility of the suction cups makes it possible to draw several cards successively from the transfer station, before it is necessary for the sensing arm 250 and switch 248 to call for more cards. Then the feeder may operate to advance several cards into the transfer station before it is de-energized.

Signal device

To warn the operator when the supply of sheets on the belt members is approaching the point where replenishment of the supply is needed, a suitable signal device is provided. This signal device includes a feeler arm 258 adapted to engage the sides of the sheets somewhat behind the point at which the upper follower member would otherwise engage the switch arm 138 to de-energize the vacuum pump and sheet feeding mechanism. This feeler arm 258 is connected to a suitable switch 260. The latter is connected in turn to a signal light or other signal device 262, by appropriate wiring 264, 266 and 268. The switch and signal light are connected by these wires to a suitable current source (not shown) in known manner.

As long as the supply of sheets extends back far enough to engage the feeler arm 258, the signal light 262 will be de-energized. If the rearmost sheet passes toward the transfer station from the feeler arm 258 so that no sheet is in engagement with the arm, the position of the arm will be permitted to change and the switch 260 will cause the signal light to be energized. Thus the operator will receive timely warning that additional sheets must be supplied.

The desired further sheets may be inserted as shown in dotted outline in Figure 1. For this purpose, the lower follower arm 68 is first retracted to the dotted line position of Figure 1. After added sheets are inserted, they are pushed firmly toward the transfer station and against the rearmost sheet of the previous supply. The upper follower arm is then lifted, clutch knob 200 pushed inwardly, and the follower reinserted above and behind the rear sheet of the new supply.

Accommodation of different sheet sizes

One of the possible uses of the present sheet feeding apparatus is the feeding of circuit boards or other electrical component boards to the conveyor member 30 for further processing. In many applications, the size of the board will vary. In order that the present apparatus

may have maximum utility in connection with boards of different sizes, provision has been made for universal adjustment to accommodate variations in both dimensions of the boards.

As previously described in connection with Figure 1, the boards are engaged by an upper guide member 14 located just ahead of the transfer station at which the leading board 18 is to be located. The upper guide member 14 is normally positioned a predetermined distance above the belt members which is less than the vertical length of the individual boards or sheets themselves. Thus the guide member 14 engages the upper edges of the sheets and requires them to be tilted to the desired predetermined angle as the sheet passes into the transfer station.

The vertical location of the upper guide member 14 may be changed or adjusted along the line of desired inclination of the sheets by the mechanism already described in connection with Figs. 2 and 3. Once this upper guide is placed in its adjusted position, it will engage only those sheets located just behind the transfer station. Thus the guide location provides a free path through which the leading sheet can be moved upwardly as well as longitudinally away from the transfer station.

The position of the lower edge of each board which reaches the transfer station is defined by the upwardly inclined ramp or stationary guide portions shown for example at 16 in Figure 1. A plurality of these ramp or guide portions are provided by means of the arrangement shown in Fig. 2.

In this figure, a cross bar 270 extends across the machine below the level of the upper surface of the belts and somewhat ahead of the belt driving pulleys. A hub portion 272 is mounted on the rod 270 for axial adjustment along the rod. This hub portion carries a fixed guide and support member 273 which has an upwardly inclined ramp portion 274 similar to the portion 16 of Figure 1. A clamping screw 275 maintains this guide in its adjusted position on rod 270. This screw can be loosened for adjustment of the guide laterally across the direction of feed to accommodate different sheet widths. A similar adjustable guide member is carried by a hub portion 276 and extends rearwardly at 278, with the inclined ramp portion 16 previously noted. For one extreme edge of the boards, a fixed guide 280 is provided with a ramp portion 281.

The parts are shown in Fig. 2 adjusted for the maximum width of sheet for which the apparatus is designed. If narrower sheets are to be processed, the support member 273 and its ramp portion 274 will be shifted toward the belt 36 far enough to accommodate one edge of the desired smaller size sheets when the other edge of such sheets is carried by the fixed guide 280 and ramp 281. The belt member 38 can then be adjusted away from belt 36 to provide a moving support for the edge of the smaller size sheet. Fixed belt 12 will still be operative as a means of driving the follower member 68, even though it will not engage the bottom of a narrower board. The desired adjustment of the central belt member 38 is readily achieved by adjustment of the clamping screw 281 (Fig. 5) by which the pulley 44 is secured to shaft 46. A similar adjustment is provided for the rear pulley 52.

The invention also provides means for adjustment of the guide member 66 to accommodate narrower sheets than those for which the device is set in Fig. 2. For this purpose, the guide 146 has vertically depending end portions. The forward end is carried in a hub 282 and is secured in a desired vertically adjusted position by a set screw 284. The hub portion 282 is connected in turn to a laterally adjustable hub 286 mounted for axial movement along the rod 270. The clamping screw 288 holds this end of the assembly in its adjusted position.

Similarly, the rearwardly located depending end of guide member 66 is received in a hub portion 290 on

which it is secured for vertical adjustment. Portion 290 in turn is connected to a laterally movable hub 292 which can be clamped in a desired adjusted lateral position on laterally extending guide rod 294. Thus the guide member 66 for one edge of the sheets is universally adjustable both vertically to accommodate sheets of different vertical dimensions and laterally to accommodate sheets of different width.

The adjustments of the guide are, of course, coordinated with the adjustments of the middle belt member and the forward ramp portions 274 and 16. Similarly, the position of the upper follower 124 and the upper guide portion 14 may be adjusted laterally to accommodate different widths, so that the force applied by follower 15 124 can be effectively centered across the width of boards of different dimensions. The provision of an adjustable central belt member, with fixed outer belt members, provides a convenient assembly which permits the use of different board widths and yet simplifies the 20 driving engagement of the follower members 68 with the outside belt for all board sizes.

In conclusion, it should be noted that the sheet feeding apparatus described in detail in the foregoing application substantially accomplishes the objectives set forth at the 25 beginning of this specification and provides a convenient, economical and efficient device for the supply of a plurality of sheets successively to a transfer station. While this apparatus has been particularly designed for the relatively rigid circuit boards utilized in the automatic 30 assembly of electrical components, many features of the invention described herein will be applicable to other uses. Since minor variations and changes in the exact details of the apparatus features will be apparent to persons skilled in this field, it is intended that this invention shall cover all such changes and modifications as fall within the spirit and scope of the attached claims.

Now therefore we claim:

1. Sheet supply means comprising at least one belt member having a portion adapted to engage one edge 40 of each of a plurality of sheets and move said sheets forwardly toward a transfer station at one end of said portion, rotary shaft means for driving the belt member portion toward said station, a follower member having a portion engaging the rear surface of at least one rearwardly located sheet, a rotary member, means for moving said follower member toward said station in response to rotation of said rotary member, and connecting means between said rotary shaft means and said rotary member for driving the latter and moving said follower member 50 at the same rate and direction as said belt portion, said connecting means including manually operable clutch means for selectively disconnecting the rotary member and shaft means for independent withdrawal of the follower member during insertion of additional sheets.

2. Sheet supply means according to claim 1, having a second follower member adapted to engage the rear surface of at least one rearwardly located sheet, means for releasably clamping said second follower member to said belt member portion for movement thereby, and manually operable releasing means for said clamping means.

3. Sheet supply means comprising at least one belt member having a portion adapted to engage the edges of a plurality of sheets and move said sheets on edge toward a transfer station at one end of said portion, a follower member engaging a rearwardly located sheet, a flexible tensioning member connected to said follower member, a weight member to which said tensioning member is connected, said weight member urging the tensioning member in a direction to pull said follower and said sheets toward the transfer station, and a rotary member driven at substantially the same peripheral speed as said belt member and in synchronism therewith, a portion of said flexible tensioning member between said weight and said follower being positioned in driving engagement 65 with said rotary member and thereby synchronizing the 70 75

11

movement of the follower, under the urging of said weight, with the movement of said belt.

4. Sheet supply means according to claim 3 having manually operable clutch means between said rotary member and said belt member thereby providing free movement of the rotary member and tensioning member when the clutch is disengaged for resetting movement of the follower member behind an added plurality of sheets,

5. Sheet supply means comprising at least one belt member having a horizontal portion adapted to engage the lower edges of a plurality of sheets and move said sheets on edge toward a transfer station at one end of said portion, means for driving said belt to move said portion toward the station, a guide member engaging the upper edges of the leading sheets just before they reach said station, the guide member being spaced perpendicularly above the belt a distance less than the vertical dimension of the sheet and thereby insuring tilting of each sheet at a predetermined angle to the belt with its upper edge slightly behind the lower edge as the sheet reaches the transfer station, and at least one follower member engaging a rearwardly located sheet and holding said sheet at an angle substantially similar to said predetermined angle.

6. Sheet supply means according to claim 5 in which said guide means is located behind said transfer station, the leading sheet, when located exactly at said transfer station, being supported at said predetermined angle by engagement with the rearwardly located sheets, the relative location of the guide member providing a clear path for forward and upward movement of the leading sheet out of said transfer station.

7. Sheet supply means according to claim 5 in which said one follower member engages the upper portion of a rearwardly located sheet and is supported thereby, and a flexible tensioning member connected to said follower and urging it toward said station.

8. Sheet supply means according to claim 7 in which

12

the driving means for said belt includes a disengageable clutch and a rotary drum driven through said clutch, said flexible tensioning member engaging said drum and being driven thereby to urge the follower member toward the transfer station.

9. Sheet supply mechanism comprising at least one belt member having a portion adapted to engage the edges of a plurality of sheets and move said sheets toward a transfer station at one end of said portion, 10 first and second follower members each adapted for engagement with a rearwardly located sheet to urge said sheets toward said station, means releasably connecting said first follower member to said belt portion to move the rearwardly located sheets with the belt, manually 15 operable releasing means for said connecting means providing for disengagement of the connecting means and relative rearward movement of said first follower member along said belt for insertion of additional sheets, and maintaining means for maintaining the second follower member in engagement with the existing supply of sheets 20 and urging said sheets toward the transfer station during disengagement of said first follower member and insertion of said additional sheets, said maintaining means including a flexible tensioning member and the second follower member is supported solely by engagement with said sheets under the urging of said flexible tensioning member.
